METHOD AND APPARATUS FOR PREPARING
COMBUSTIBLE FUEL MIXTURESCarl N. Bergstrom, deceased, late of Portland, Oreg., by
Bartlett F. Cole, executor, Mead Bldg., Portland, Oreg.

Filed May 6, 1957, Ser. No. 657,281

1 Claim. (Cl. 123—119)

This invention pertains to the combustion of fuels, 15 and relates particularly to a novel method and apparatus by which to improve the operation of internal combustion engines.

The operation of internal combustion engines is attended by many recognized disadvantages. For example, the formation of carbon deposits within the combustion chambers and upon other of the working parts ultimately results in the development of an exhaust which includes excessive amounts of solid particles and oil. In valve type engines this accumulation of carbon contributes materially to the sticking of valves and otherwise faulty operation of the engine. In gasoline type engines, and particularly those of high compression ratios, it is necessary for optimum operation to use premium quality gasolines which include additives to control the rate of combustion and thus reduce to a minimum the disconcerting rattle or "knock" normally attending the use of regular types of gasoline. The operation of internal combustion engines also is attended by an exhaust which includes substantial amounts of poisonous carbon monoxide.

It is a principal object of the present invention to provide a method and apparatus by which internal combustion engines are rendered operable without the disadvantages enumerated above.

Specifically, it is an important object of the present invention to provide a method and apparatus by which to minimize in the operation of internal combustion engines the exhaust of solid particles and oil.

Another important object of this invention is to provide a method and apparatus by which to eliminate carbon monoxide from the exhaust gases of internal combustion engines.

A further important object of the present invention is the provision of a method and apparatus by which to minimize the formation of carbon deposits on the working parts of internal combustion engines.

Still another important object of this invention is the provision of a method and apparatus by which internal combustion engines of the gasoline type may be operated with regular gasolines without the attendance of rattle or "knock" which heretofore has characterized such operation.

A still further important object of this invention is to provide apparatus for achieving the foregoing objectives, which apparatus is of simplified construction for economical manufacture, which may be readily installed upon internal combustion engines of all types, and which is operable with maximum efficiency and with a minimum of maintenance and repair.

The foregoing and other objects and advantages of the present invention will appear from the following detailed description, taken in connection with the accompanying drawing, in which:

Figure 1 is aforeshortened view in side elevation of apparatus for preparing combustible fuel mixtures, embodying the features of the present invention, the same

being illustrated in conjunction with the intake system of an internal combustion engine, parts being broken away to disclose details of construction;

Figure 2 is aforeshortened sectional view taken along the line 2—2 in Figure 1; and

Figure 3 is a schematic diagram illustrating a form of electrical circuit associated with the apparatus illustrated in the preceding views.

In its basic concept, the present invention involves the introduction of a quantity of ozone into the combustion chamber of an internal combustion engine, preliminary to the combustion of air and combustible fuel. This may be achieved in many ways. For example, ozone may be injected directly into the combustion chamber, independently of the air and combustible fuel, or in admixture therewith. Alternatively, ozone may be generated from the air being introduced to the combustion chamber wherein, as in diesel engines and some types of gasoline engines, the combustible fuel is introduced by injection. In those types of internal combustion engines which employ carburetors to admix air and gasoline prior to introduction into the combustion chamber, ozone may be introduced into the mixture or into the air preceding mixture with fuel. In the preferred embodiment of the invention ozone is generated from the air either before or after the introduction of gasoline.

In the embodiment illustrated in the drawing, apparatus is provided for generating ozone to be introduced into the combustible fuel intake system of an internal combustion engine. The apparatus includes a housing for an ozone generator, the housing having an air inlet and an air outlet adapted for connection to the intake system of an internal combustion engine.

Thus, in the specific embodiment illustrated, the housing is formed of two hollow sections 10 and 12, adapted for releasable interconnection by means of interengaging threads 14. The upper section 10 is provided with a hollow extension 16 adapted to releasably receive the hollow supporting hub 18 of an air cleaner housing 20. A clamp 22 may be provided if desired for securing the air cleaner housing firmly to the inlet extension.

The lower section 12 of the housing preferably is provided with a lateral bracket 24 which functions, for example in conjunction with a mounting frame 26 and bolt 28, to secure the housing on the engine or other suitable support. The lower section also is provided with a threaded opening adapted to releasably receive the complementary threaded section of a lamp socket base 30. The socket base is centrally apertured to receive the socket end of an electric ozone lamp 32, of conventional construction.

The lower section 12 also is provided with a hollow extension 34 which functions as an air outlet for the housing. This outlet extension is adapted to receive thereover one end of a hollow conduit 36, preferably of the flexible type and constructed of a material which is inert to deleterious action of ozone. Thus, the conduit may be made of metal or of various types of synthetic plastic materials, well known in the art.

Means is provided for connecting the opposite end of the conduit 36 to the fuel intake system of an internal combustion engine. In the embodiment illustrated in the drawing, such means is provided in the form of an annular adapter having a peripheral wall 38 and spaced face flanges 40, 42. The face flanges are apertured transversely to form a central opening 44. The space between the peripheral wall and the spaced face flanges forms an annular channel 46 which communicates with a lateral hollow extension 48. The extension is adapted to receive thereover the end of the flexible conduit 36 opposite the outlet 34.

The adapter is proportioned for interposition between sections of the air and fuel intake system of an internal combustion engine. As illustrated in the drawing, adjacent sections 50, 52, of the intake system are provided with connector flanges adapted to be secured as by means of connecting bolts 54. These adjacent sections of the intake system are hollow, as indicated, and the openings 44 in the spaced side flanges of the adapter preferably are proportioned to correspond and register with the bore of the intake sections. Thus, the adapter may be interposed between said intake sections and secured against displacement by means of the frictional pressure exerted thereon by the spaced flanges, by tightening the connecting bolts.

The adjacent sections of the intake illustrated in the drawing may represent a portion of the intake system located, for example, between the carburetor and intake manifold of a gasoline engine, or it may represent a portion of the intake system which precedes the inlet to the carburetor, as for example, the portion between the carburetor inlet and the air cleaner provided for filtering the air to be introduced into the combustion chamber.

In Figure 3 of the drawing there is shown a simplified electrical circuit for the ozone lamp 32. One terminal of the lamp is grounded, as indicated, and the other terminal is connected through the ignition switch 56 to the positive terminal of the engine battery 58, thus providing for activation of the lamp when the ignition switch is turned on.

In the operation of the apparatus described hereinbefore, closing of the ignition switch 56 energizes the ozone lamp 32. With the engine running, the reduced pressure or partial vacuum in the intake system causes a draft of air therethrough in the direction indicated by the arrows in Figure 1. This draft may be a flow of air to a carburetor, or it may be a flow of air and atomized gasoline from a carburetor to the intake manifold. In either case, the partial vacuum creating the draft also causes air to be drawn through the air cleaner housing 20 into the upper space of the housing surrounding the ozone lamp 32. This air then is directed downwardly around the ozone lamp in close proximity therewith, thereby generating ozone from the oxygen content of the air. This mixture of air and ozone then is drawn through the outlet 34 of the housing and through the flexible conduit 36, to the annular space 46 defined by the adapter wall, from whence it enters the intake system of the engine. From this intake system the mixture of air, combustible fuel and ozone enters the combustion chambers of an engine, whereupon it is compressed and exploded, in conventional manner.

In the case of diesel engines, the apparatus disclosed in the drawing preferably is connected to the air intake system, and the resulting mixture of air and ozone is introduced into the combustion chambers where it is mixed with combustible fuel which is injected therein during the

compression cycle. It will be apparent to those skilled in the art that suitable means also may be provided for introducing ozone into the combustion chambers of jet engines and other devices such as fuel combustion furnaces, within the contemplation of this invention.

In the operation of internal combustion engines of the gasoline type, it has been found that the method and apparatus of the present invention function effectively to reduce substantially the solids and oil particles emitted from the exhaust. Even in worn engines, the characteristic cloud of smoke which normally is emitted from the exhaust, particularly after extended deceleration, is substantially eliminated. Furthermore, the exhaust gas is completely free of poisonous carbon monoxide. Periodic inspection of the piston rings, valves and spark plugs after operation with the apparatus of this invention evidenced a progressive decrease in carbon deposits until, after about one thousand miles of operation, carbon residue was reduced to a minimum. Operating performance was improved even with the use of regular gasolines containing no anti-knock additives, and without the characteristic rattle or "knock."

It will be apparent to those skilled in the art that various changes in the form, size, and specific details of construction described hereinbefore may be made without departing from the scope and spirit of this invention. Accordingly, it is to be understood that the foregoing description is primarily illustrative of the invention and is not to be considered as limiting the scope thereof.

Having now described the invention and the manner in which the same may be used, what is claimed as new and desired to secure by Letters Patent is:

For use with an internal combustion engine having an intake system for introducing a mixture of air and combustible fuel into the combustion chamber thereof, and wherein said intake system includes a pair of conduit sections releasably connected together, apparatus for preparing combustible fuel mixtures, comprising an electrically actuated ozone lamp, a hollow housing therefor having an air inlet and an air outlet interconnected by a space surrounding the lamp, conduit means connected at one end to the air outlet, and annular adapter means connected to the opposite end of the conduit means and adapted for insertion transversely between the hollow conduit sections of the said intake system of the engine.
